(57) **CLAIM**

The ornamental design for a control valve, as shown and described.

DESCRIPTION

FIG. 1 is a front, top, and right-side view of a control valve showing our new design.

FIG. 2 is a rear, top, and right-side view of the control valve; and,

FIG. 3 is a left side and bottom view of the control valve. The broken lines represent portions of the control valve that form no part of the claimed design.

1 Claim, 3 Drawing Sheets

FIG. 1

FIG. 2

FIG. 3
